US00D990825S

(12) **United States Design Patent** (10) Patent No.: **US D990,825 S**
(45) Date of Patent: ** Jul. 4, 2023

(54) **HEAD STRAP**

(71) Applicant: **HUIZHOU HUIYANG DISTRICT XINWEI LIANSHENG PLASTIC PRODUCTS FACTORY**, Huizhou (CN)

(72) Inventor: **Sheng Ling**, Huizhou (CN)

(73) Assignee: **HUIZHOU HUIYANG DISTRICT XINWEI LIANSHENG PLASTIC PRODUCTS FACTORY**, Huizhou (CN)

(**) Term: **15 Years**

(21) Appl. No.: **29/824,937**

(22) Filed: **Jan. 27, 2022**

(51) LOC (14) Cl. **14-02**
(52) U.S. Cl. **USPC D2/865; D14/372**

(57) **CLAIM**

The ornamental design for a head strap, as shown and described.

DESCRIPTION

FIG. 1 is a perspective view of a head strap showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view thereof;

FIG. 10 is a perspective view of the head strap where the head strap is assembled with VR glasses; and,

FIG. 11 is an exploded perspective view thereof.

The broken lines along the head strap depict portions of the head strap that form no part of the claimed design. The broken line outline of the VR glasses in FIGS. 10 and 11 depict environmental structure associated with the head strap that form no part of the claimed design.
